Attorney.

UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed July 26, 1919. Serial No. 318,481.

To all whom it may concern:

Be it known that I, ALFRED G. F. KUROWSKI, a citizen of the United States, formerly a citizen of Germany, residing in Brooklyn Borough, in the county of Kings, city and State of New York, have invented certain new and useful Improvements in Typewriting Machines, of which the following is a specification.

10 This invention relates to devices used in connection with the round platens of front-strike typewriting machines, for writing cards, especially stencil address cards, and the objects of the invention are to provide 15 simple and efficient means for guiding and line-feeding the card, and to provide means whereby the card may be inserted at different desired points along the platen, thereby saving undue wear of the platen at any one 20 place and gaining other advantages.

The carrier for the card is in the form of a bar which normally occupies a position below the front of the platen, and which, at its ends, is provided with upstanding racks 25 meshing with crown gears on the ends of the revoluble platen, to form, at the front of the platen, a U-shaped card-holding frame. The provision of crown gears is valuable because it enables the rack to stand about 30 flush with the foremost portion of the platen, so as not to occupy a space in front of the platen, and so as to pass freely by ribbon and other devices, usually arranged at the front of the platen.

35 The said bar is guided at its ends in vertical slots formed in the ends of the platen frame, and is in the form of a channel, to combine stiffness with lightness, and also to receive a pair of clips which clip the lower 40 portion of the card at opposite ends. These clips are independently adjustable, to accommodate cards of different widths, and also to permit adjustment of the printing field to different positions along the platen, 45 each clip having a simple releasable clamp, to permit such adjustment and lock the clip wherever placed. Each clip is in the form of an upstanding spring lip, which is bent forwardly, to facilitate insertion of the card, 50 and a mount whereon said clip is secured,

said mount in the form of a thin plate which stands in the same plane with the card, the edge of the mount serving as a gage for positioning the card endwise.

Other features and advantages will hereinafter appear. 55

In the accompanying drawings,

Figure 1 is a fragmentary plan view of a typewriter carriage, showing the present invention as applied thereto. 60

Figure 2 is a front view of the same.

Figure 3 is a fragmentary sectional side view.

Figure 4 is a perspective view of a card-holding clip, as mounted in the card-holding 65 bar.

Figure 5 is a spread perspective view of the card-holding clip and its finger-piece.

Figure 6 is a perspective view of the racks, the card-holding bar, and a stencil card, 70 mounted therein for typing purposes.

Figure 7 is a plan view of the parts seen in Figure 4.

Figure 8 is a perspective view of a wing plate and its extensions. 75

The revoluble platen 10 is shown as journaled by means of its axle 11 in the frame ends 12, and as adapted to be revolved by the knobs 13, or by the line-space wheel 14 of the typewriting machine, said line-space 80 wheel being adapted to be engaged by a pawl 15, pivoted on a slide 16, which is adapted to be driven by a line-space handle 17.

When it is desired to write upon a card, such as the stencil card 18, shown in Figures 85 2 and 6, the card is slipped into the channel 19 in the upper side of a card holding channel bar 20, having within its channel card-holding clips 21. The channel bar 20 is located at the front of the platen 10 below its axis and below the printing line and is connected at each end to the lower end of a vertical rack 22, each rack held by means of its guides 23, at its end 12 of the platen frame, so that it is constantly in mesh with 90 a crown gear 24, fast upon the end of the platen, adjacent it, and having an outside periphery flush with that of the platen. The front surface of each rack 22 is substantially flush with the periphery of the 95 100

2
gear 24, so that these racks lie substantially within a plane tangent to the periphery of the platen 10, as shown in Figures 1 and 3. When it is desired to insert a card 5 into the channel 19, the platen is advantageously rotated in line-feeding direction until the channel bar 20 is in its upper position, thus bringing the bar almost up to the printing line, at which the type 25 prints 10 through the ribbon (not shown). The bar 20 rises to this position when the platen is rotated forwardly, inasmuch as the racks 26. The clip-carrying bar 20 and the upper standing racks 22 together form a card-holding frame.

In order to retain the card 18 in the channel 19, each clip 21 is shown as comprising a card-gripping friction wing 27, which is held 20 by a screw 28 to a lug 29 projecting from the body 30 of the clip, which lies within the channel 19. The jaws, arms or wings 27 are bent outward at their upper ends 31, and have considerable resiliency, and are so positioned that they tend to press the card 18 against the rear side 32 of the channel and against the front side of the platen. In order to give the bodies 30 a sufficient hold on the channel, to enable them to exert sufficient 30 pressure upon the card 18, there is fast to each body a plate 33 formed as an extension of the wing 27. Each plate 33 curves over the rear side of the channel bar 20, and extends downwardly, and hooks its turned-up 35 extension 34 around a strengthening web 35, formed integral with the bottom of the channel bar. This web of the channel bar gives it great rigidity, combined with the lightness and the small dimensions necessary to keep 40 it from interfering with the parts often occupying the space below and in front of the platen in various makes of typewriting machines. The clips 21 are advantageously made separately from the channel bar, and 45 then slipped on over the ends before the racks 22 are fastened thereto.

In order to hold the clips 21 in positions upon the channel bar, in which their inwardly-facing ends 36 will bear frictionally 50 against and serve as gages for the adjacent end of the inserted card or stencil frame 18, each body has pivoted thereto, at 37, a friction-locking lever 38, forming a finger-piece, comprising, in the form herein shown, a U-shaped friction bend 39 and a turned-over 55 upper extension 40, having an apron 41 adapted to come down outside of the front of the channel bar, and thus bind the friction bend 39 against the inner face sufficiently to hold the clip in place. To enable the lever 60 38 to be released, it is shown as provided with an extension 42, having a turned-over end 43, forming a finger-piece lip lying close to, but slightly above, the channel bar, thus 65 enabling the finger of the typist to easily

grasp it and lift it, to enable the clip 21 to be slid along to a position on the channel bar 20.

It will be observed that the aprons 41 lie entirely outside and considerably beyond the 70 margins of the card 18, with the result that they need never come near the ribbon-vibrating or type-guide mechanism in any ordinary machine. These aprons, however, are advantageously quite thin, with the result 75 that if the typewriter carriage should be carried so far beyond its needed travel as to carry the aprons past any type-guide or ribbon-vibrator, it will be likely to clear it. The flare of the wings 27 need be very small, 80 and need not bring them further forward than the front edge of the channel bar 20.

In order to steady the channel bar 20 as it moves up and down with the platen, there 85 may be provided, at each end, a guiding lug or roll 44 extending into a slot 45 in the adjacent end plate 12, thus making it possible to insure that the channel bar shall always travel in a path clear of any interfering mechanism. The usual bottom feed rolls 90 may be omitted, and, if desired, upper front feed rolls 46, mounted in any desired or usual way, may run upon the edges 47 of the card 18 to hold it upon the platen. If the card is a stencil plate, it will have thick 95 edges which are never written on, with the result that the rolls 46, running on these edges, will in no way interfere with the writing.

In order to give the wings 27 a firmer hold 100 upon a card 18, the lower corners 48 may be given a slight inward twist, with the result that they tend to dig into the card very slightly, not, however, enough to mar it or to prevent its easy withdrawal.

It is to be noted that the device of the present invention leaves the front of the platen clear of obstructions and provides for the quick insertion and removal of the cards. 105 It is to be further noted that the card-holding frame formed by the card-holding bar 20 and the end bars or racks 22 is U-shaped and open at the top, so that the comparatively 110 stiff work-piece, such as the stencil card 18, may be held by its lower edge only, to project upward from the card-holding bar 20 into the open space provided by the U-shaped frame, past the printing line at the front of 115 the platen 10.

Variations may be resorted to within the 120 scope of the invention, and portions of the improvements may be used without others.

Having thus described my invention, I claim:

1. In a front-strike typewriting machine, 125 the combination with a revoluble platen, of a card-holding frame, crown gears at the ends of the platen and substantially flush with the periphery thereof, racks lying substantially within a plane tangent to the pe- 130

- riphery of the platen and meshing with said gears and forming the ends of the frame, and a card-holding cross-bar forming a part of the frame and connecting said racks. 5
2. In a front-strike typewriting machine, the combination with a revoluble platen, of a channel bar connected to the platen, clips comprising bodies slidable in the channel, extensions of said bodies above the channel, and resilient arms on said extensions adapted to press against the platen a card inserted in the channel. 10
- 10 10. In a front-strike typewriting machine, the combination with a revoluble platen, of a channel bar connected to the platen, clips comprising bodies slidable in the channel, extensions of said bodies above the channel, resilient arms on said extensions adapted to press against the platen a card inserted in the channel. 15
- 15 15. In a front-strike typewriting machine, the combination with a revoluble platen, of a card-holding frame, a channel bar forming the bottom of said frame, and adapted to receive the card in its channel, clips slidable along said channel and adapted to hold the card, and means for advancing the frame with the revolving of the platen. 20
- 20 4. In a front-strike typewriting machine, the combination with a revoluble platen, of a card-holding frame, a channel bar forming the bottom of said frame and adapted to receive the card in its channel, clips slidable along said channel and comprising thin arms extending over and catching under the bottom of said bar, and means at the ends of the frame connected to the ends of the platen to advance the frame with the revolving of the platen. 25
- 30 35. In a front-strike typewriting machine, the combination with a revoluble platen, of a channel bar connected to the platen, clips slidable in said channel comprising jaws to frictionally hold a card, and a finger-piece connected to each clip and adapted to be swung to engage the bar to lock its clip in position. 40
- 45 6. In a front-strike typewriting machine, the combination with a revoluble platen, of a channel bar connected to the platen, clips comprising bodies slidable in the channel, and wings upon said clips adapted to hold a card inserted in the clips. 50
- 55 7. In a front-strike typewriting machine, the combination with a revoluble platen, of a channel bar connected to the platen, clips comprising bodies slidable in the channel, wings upon said clips adapted to hold a card inserted in the clips, means for detaining the clips at any set position, and extensions of said clips underlying said bar to hold them in the channel. 60
- 60 8. In a front-strike typewriting machine, the combination with a revoluble platen, of a channel bar connected to the platen, clips comprising bodies slidable in the channel, wings upon said clips adapted to hold a card inserted in the clips, finger-pieces piv- 65
- oted upon said bodies, and friction members fast upon said finger-pieces and adapted to engage within the channel to hold the clips where set. 70
9. In a front-strike typewriting machine, the combination with a revoluble platen, of a channel bar connected to the platen, clips comprising bodies slidable in the channel, extensions of said bodies above the channel, and resilient arms on said extensions adapted to press against the platen a card inserted in the channel. 75
10. In a front-strike typewriting machine, the combination with a revoluble platen, of a channel bar connected to the platen, clips comprising bodies slidable in the channel, extensions of said bodies above the channel, resilient arms on said extensions adapted to press against the platen a card inserted in the channel, finger-pieces pivoted upon said bodies, and friction members fast upon said finger-pieces and adapted to engage within the channel to hold the clips where set. 80
11. In a front-strike typewriting machine, the combination with a revoluble platen and a platen frame in which it is journaled, of a card-holding bar, crown gears upon the ends of the platen substantially flush with its surface, racks connected to said bar and guided in said frame and engaging said gears substantially flush with the periphery thereof, and a line-spacing device for the platen. 85
12. In a front-strike typewriting machine, the combination with a revoluble platen and a platen frame in which it is journaled, of a bar extending along the platen at the front and below the axis thereof, card-holding clips upon said bar comprising wings adapted to press a card against the platen, crown gears upon the ends of the platen substantially flush with its surface, racks connected at their lower ends to said bar and guided in said frame and engaging said gears substantially flush with the periphery thereof, and a line-spacing device for the platen. 90
- 100 13. In a front-strike typewriting machine, the combination with a revoluble platen, of a channel bar connected to the platen, clips comprising bodies slidable in the channel, said bodies adapted to frictionally engage the ends of a card, and wings upon said clips adapted to bear upon the front face of the card to hold it against the platen. 105
- 115 14. In a front-strike typewriting machine, the combination with a revoluble platen and a platen frame in which it is journaled, of a channel bar having thin walls adapted to receive the bottom of a card, a stiffening web extending below said bar, and means connecting said bar to move with the turning of the platen. 120
- 125 15. In a front-strike typewriting machine, 130

the combination with a revoluble platen, of a channel bar connected to the platen, clips comprising bodies slidable in the channel, finger-pieces pivoted upon said bodies and 5 extending away from the card-holding sides of the clips, friction spring devices adapted to lie with the channel to hold the clips and forming part of the finger-pieces, and lips on said finger-pieces standing slightly clear 10 of the bar to enable the operator's fingers to grip the finger-pieces.

16. In a typewriting machine, the combination with a card-holding bar having a channel to accommodate the card, of a clip 15 having a body lying within the channel to bear against the card, a wing extending above the channel to bear against the face of the card, a lever pivoted to the body and lying within the channel, a friction surface 20 upon said lever adapted to bear against one side of the channel, an extension of the lever having a turned-over end to engage upon the outside of the bar to additionally frictionally hold it, and a lip upon the lever 25 lying above the bar to enable the operative's finger to seize it.

17. In a typewriting machine, the combination with a card-holding bar having a channel to accommodate the card, of a clip 30 having a body lying within the channel to bear against the card, a resilient wing extending above the channel to bear against the face of the card, a lever pivoted to the body and lying within the channel, a friction surface 35 upon said lever adapted to bear against one side of the channel, an extension of the lever having a turned-over end to engage upon the outside of the bar to additionally frictionally hold it, a lip upon the 40 lever lying above the bar to enable the operative's finger to seize it, and a thin bracket fast to the body and extending over the side of the bar and beneath it to hold the body in the channel.

45. 18. In a front-strike typewriting machine, the combination with a revoluble platen and a platen frame in which it is journaled, of a card-holding frame, a channel-bar forming the bottom of said frame for receiving the 50 lower edge of the card in its channel, clips slidable along the channel-bar for holding the card, racks extending upward from the ends of the channel-bar and forming the ends of said frame, gears carried by the ends 55 of the platen and meshing with said racks, and guides on the platen frame for guiding the card-holding frame.

19. In a front-strike typewriting machine, the combination with a revoluble platen and 60 a platen frame in which it is journaled, of a U-shaped card-holding frame open at the top, a card-holding bar forming the bottom of said frame, for holding a comparatively stiff card by its lower edge to project upward 65 from the bar into the open space pro-

vided by the U-shaped frame and past the printing line at the front of the platen, racks connected at their lower ends to the ends of said bar and forming the ends of said frame, gears carried by the ends of the platen and 70 meshing with said racks, and guides on the platen frame for guiding the card-holding frame.

20. In a front-strike typewriting machine, the combination with a revoluble platen, of a U-shaped card-holding frame open at the top, a card-holding bar for carrying the card forming the bottom of said frame, for holding a comparatively stiff card by its 75 lower edge to project upward from the bar into the open space provided by the U-shaped frame and past the printing line at the front of the platen, racks connected to and extending upward from the ends of said bar and forming the ends of said frame, and 80 gears carried by the ends of the platen and meshing with said racks. 85

21. In a front-strike typewriting machine, in combination, a revoluble platen, a platen frame in which the platen is journaled, a card-holding bar extending lengthwise of the platen in front and below the printing line thereof, card-holding means adjustable along the bar for holding a card upstanding above the bar in different positions longitudinally thereof, racks connected at their lower ends to the ends of the bar and forming with the bar a card-holding frame, gears carried by the ends of the platen and meshing with the said racks, and guides on the 90 platen frame for guiding the card-holding frame. 95

22. In a front-strike typewriting machine, in combination, a revoluble platen, a card-holding bar extending lengthwise of the platen in front and below the printing line thereof, card-holding means on and adjustable along the bar for holding a card upstanding from the bar in different positions longitudinally thereof, racks connected at 100 their lower ends to the ends of the bar, and gears carried by the ends of the platen and meshing with said racks for advancing the card as the platen is revolved. 110

23. In a front-strike typewriting machine, the combination with a revoluble platen, of a card-holding bar extending lengthwise of the platen at the front thereof below the printing line for engaging and holding the lower edge of the card, a pair of end gages for the card carried by and slidably adjustable along the card-holding bar, and means for concomitantly line-spacing the platen and the card-holding bar. 115

24. In a front-strike typewriting machine, the combination with a revoluble platen, of a card-holding bar extending lengthwise of the platen at the front thereof below the printing line for engaging and holding the lower edge of the card, a card-holding de- 120 125 130

vice mounted on and adjustably slidable along the card-holding bar, and means for concomitantly line-spacing the platen and the card-holding bar.

5 25. In a front-strike typewriting machine, the combination with a revoluble platen, of a card-holding bar extending lengthwise of the platen at the front thereof below the printing line for engaging and holding the 10 lower edge of the card, a pair of end gages

for the card carried by and slidably adjustable along the card-holding bar, a card-holding clip carried by each of the end gages, and means for concomitantly line-spacing the platen and the card-holding bar. 15
